UNITED STATES PATENT OFFICE

CHARLES LORBER, OF LOUISVILLE, KENTUCKY

KEY CASE

Application filed June 28, 1929. Serial No. 374,350.

This invention relates to key cases such as are used for carrying keys in the pocket and has special reference to a flexible key case.

Key cases which employ metallic plates for carrying the keys are in some cases objectionable because of their lack of flexibility. Different methods have been attempted for providing a flexible key case but I have found no method which was entirely satisfactory prior to my invention of the key case forming the present invention.

One important object of the present invention is to provide an improved general construction of flexible key case.

15 A second important object of the invention is to provide an improved form of flexible key case wherein the keys are attached to a flexible strip, the strip being preferably of like material with the case itself.

20 A third important object of the invention is to provide improved means for anchoring the keys to the key case.

With the above and other objects in view as will be hereinafter apparent, the invention 25 consists in general of certain novel details of construction and combinations of parts hereinafter fully described, illustrated in the accompanying drawings and specifically claimed.

30 In the accompanying drawings like characters of reference indicate like parts in the several views, and:

Figure 1 is a perspective view showing the improved key case open in one of its forms.

35 Figure 2 is a perspective view of the upper part of such a key case in a slightly modified form.

Figure 3 is a view of the form shown in Figure 2 with the key holding strip or flap 40 folded backwardly.

Figure 4 is a section on the line 4—4 of Figure 1.

Figure 5 is a section on the line 5—5 of Figure 2.

45 Figure 6 is a detail view of a portion of the back of one of the flaps or strips used in connection with this invention.

Figure 7 is a perspective view of a further modification with the key hooks connected 50 thereto.

Figure 8 is a view of the upper part of Figure 7 with the key hooks and anchors removed.

Figure 9 is a section on the line 9—9 of Figure 7.

Figure 10 is a view of one form of the anchor used herewith.

Figure 11 is a view of the second form of anchor.

Figure 12 is a view of a third form of anchor especially used with the construction shown in Figures 7 to 9.

Figure 13 is a perspective view showing the last form of the hanger and disclosing the flattened head on the hook shank.

In each instance the key case consists of a body having a central portion 10 and cover flaps 11 which may be folded over on the body and held in folded position by snap button parts 12. This body is preferably lined though I do not confine myself to any particular construction of body.

Across the top of the body in Figure 1 extends a strip 13 of flexible material, the material being preferably like that used in the body and this strip 14 is secured at all four of its edges by stitching

15. In Figures 2 and 3 there is shown a strip 15 which is formed from an extension of the body, being foldable on the front line 16 and the other three sides of this strip are 20 stitched to the body as shown at 17 in Figure 2.

In both of these forms the strip is provided with a series of spaced slots 18. In the form shown in Figures 7 and 8 the construction is much the same but it will be noted 25 that while the slots 18 of Figures 1 and 2 are rounded at the ends the strip in Figures 8 and 9 is provided with square ended slots 18'.

Through these slots extends the U-shaped central portion of an anchor member which 30 is shown at 19 as being made of round wire for use with the form in Figures 1 and 2 and at 20 as being made of flat wire. Preferably on the legs of this member are provided flattened feet 21 as shown in Figure 10 though 35 these feet may be simply extensions of the round wire as shown at 22 in Figure 11 or the whole device being of flat wire as in Figure 12 the feet 23 will also be flat. Passing 40 through this central portion in Figures 1 and

2 is a round eye 24 having an end 25 whereon is swiveled a key hook 26. In Figures 7 and 8 there is provided a square eye or stirrup 27 having an opening in its lower end through which extends the shank 28 of a key hook 29, this shank being headed as at 30 to hold it secured to the stirrup.

By this means each of the key hooks is attached independently to the strip and the flexibility of the strip is not interfered with 10 so that the key case will fit comfortably in any pocket of the wearer and will yet hold the keys very securely.

There has thus been provided a simple and 15 efficient device of the kind described and for the purpose specified.

It is obvious that minor changes may be made in the form and construction of the invention without departing from the material spirit thereof. It is not, therefore, desired to confine the invention to the exact 20 form herein shown and described, but it is desired to include all such as properly come within the scope claimed.

Having thus described the invention, what 25 is claimed as new, is:

A key case having a body of flexible material, a flexible strip at one end of the body and having all of its edges fixedly secured 30 to the body and provided with spaced vertically elongated slots, a series of key hooks, and anchor members each projecting through a respective slot and supporting a respective key hook, each of said anchor members consisting of a central U-shaped portion having 35 its legs projecting through the slot at the ends thereof and having feet extending in opposite directions from the legs of the central portion and positioned between the strip and body, said anchor member having its 40 central U-shaped portion formed of round wire to permit free movement of an object suspended thereon, said feet being formed from the ends of the wire and being of greater width and less thickness than the diameter of 45 the wire whereby the feet are given a broad bearing beneath the strip without unduly bulging the strip.

In testimony whereof I affix my signature.
CHARLES LORBER.
